UNITED STATES PATENT OFFICE.

VERNON C. TASKER, OF WASHINGTON, DISTRICT OF COLUMBIA, ASSIGNOR
TO UNITED STATES ORDNANCE COMPANY, OF WASHINGTON, DISTRICT
OF COLUMBIA, A CORPORATION OF VIRGINIA.

FIRING DEVICE FOR BREECH-LOADING GUNS.

SPECIFICATION forming part of Letters Patent No. 745,301, dated November 24, 1903.

Original application filed February 7, 1903, Serial No. 142,356. Divided and this application filed March 23, 1903. Serial No. 149,010. (No model.)

To all whom it may concern:

Be it known that I, VERNON C. TASKER, a citizen of the United States, residing at Washington, District of Columbia, have invented 5 certain new and useful Improvements in Firing Devices for Breech-Loading Guns, of which the following is a full, clear, and exact description when taken in connection with the accompanying drawings, which form 10 a part thereof.

My invention consists in non-recoiling mechanism on the gun-mounting for actuating firing mechanism recoiling with the gun and is shown in connection with substantially the same breech mechanism and firing-lock, respectively, as disclosed in my application, Serial No. 142,356, filed February 7, 15 1903, and in Letters Patent No. 710,124, granted to me September 30, 1902, although 20 I am not to be understood as limiting myself to this particular breech mechanism or firing-lock.

Having fully disclosed and claimed in the above-mentioned application and Letters 25 Patent the breech mechanism and firing-lock therein respectively set forth, a detailed description of the parts and operation thereof will not be repeated herein.

Figures 1 and 2 are rear and side elevations, respectively, of the gun and firing device. Fig. 3 is a section on the line $g-g$ of 30 Fig. 2. Fig. 4 is a side and end view of the washer T^5 of Figs. 1, 2, and 3. Fig. 5 represents a plan view of the device in simpler 35 form, the firing-handle U being in inoperative position and its operative position indicated by dotted lines; Fig. 6, a side elevation of the same; Fig. 7, a cross-section through the shaft S and the hub U' of the firing-handle.

Referring to the drawings, A represents the gun, having a hinged carrier C for the breech-block and for the firing-casing K , which contains the firing-lock and has at its outer extremity an arm K' , extending across 40 the rear face of the carrier carrying the shaft P . The upper end of the shaft P operatively engages the firing-lock. Its lower end terminates in the free arm P' for the purpose of rotating said shaft to fire the gun, said 45

arm extending forwardly and actuated by 50 the pallet S^4 , carried by the shaft S^3 , journaled in the bearing T^3 on the non-recoiling portion Y of the mount or carriage. The pallet S^4 , which engages the arm P' in firing, is extended rearwardly to permit of firing 55 the gun when not fully forward, and the shaft S^3 , which carries said pallet, is furnished with a return-spring V' and a releasing-latch S^5 , which are engaged by the hub U^9 of the firing-handle U^8 during its movement in 60 firing and released therefrom by overtravel of the handle. The firing-handle U^8 is hinged to the hub U^9 to permit of being folded rearwardly against the bearing T^3 , its lug U^2 engaging the slot T^2 in the bearing T^3 and preventing rotation of the shaft S^3 . 65

The bearing T^3 has an internal collar T^4 engaging one end of the spring V' , the other end of which engages the shaft S^3 to keep it 70 revolved to normal position. The internal collar T^4 also engages one end of a lever-return spring V^2 , its other end engaging with the firing-lever hub and tending to maintain the latter in normal position.

The firing-lever hub has an annular projection U^{10} entering the bearing T^3 and partially cut away, forming a lip U^{11} , normally engaging the latch S^5 . (See Fig. 3.) A washer T^5 (shown separately in Fig. 4) abuts the end of the bearing and carries a cam-lug T^6 , and 75 its rotation is prevented by a dowel T^7 , engaging the bearing. The relation of the parts is such that when the shaft S^3 , through the agency of the lip U^{11} , acting on the latch S^5 , has been rotated by the firing-handle far 80 enough to fire the gun the latch is depressed into the shaft by riding upon the cam-lug T^6 . This releases the shaft from the influence of the firing-lever and permits the spring V' to 85 return it to normal position. The firing-lever is stopped by the lug U^{12} on its hub meeting the bearing T^3 , and upon subsequent release of downward pressure on the firing-lever it is restored to normal position by the spring V^2 . The latch S^5 then springs again in front 90 of the lip U^{11} in position to be again actuated by downward movement of the firing-lever. 95

Figs. 5, 6, and 7 exhibit my device in a sim-

pler form, wherein the automatic release and return to position of the firing-shaft after the firing-lever has been depressed sufficiently to fire the gun is dispensed with. To this end 5 the pallet S' , carried by the shaft S , is of helicoidal form, as shown, and a horn or projection C^{19} is so positioned on the carrier C as to deflect the pallet, shaft, and firing-handle to normal position upon the return of the gun 10 after recoil in case the firing-handle is not already released from its depressed position. A single spring V rotatively actuates the shaft S to keep the pallet S' in downward and the handle U in upward position. The handle-hub U^1 is loosely mounted on the shaft 15 and carries a screw U^7 , having a projection entering the outer end of a slot S^2 , Fig. 7, in the shaft, securing the latter against endwise movement and causing it to rotate against 20 the resistance of the spring V when the handle U is depressed to fire the gun. The horn or finger C^{19} on the carrier is normally just forward of the pallet S' , and as the gun returns to position after recoil should the pallet 25 still be in its upward position this horn C^{19} automatically deflects it to normal position before it can again act upon the arm P' , and if after this from any cause the handle U should be depressed before the breech is 30 closed for the next shot the pallet S' is again automatically thrust into normal position by the horn C^{19} as the carrier swings shut. Thus the gun cannot be accidentally fired by the handle U being carelessly or accidentally 35 held in depressed position between shots. In firing the gun the pallet S' swings upwardly, and as the gun recoils the projection C^{19} acts on its under side and further deflects it slightly in order to pass to the rear, the slot 40 S^2 in the shaft S permitting this without further movement of the firing-handle U .

I claim—

1. The combination with a breech-loading gun, firing mechanism thereon, and a recoil-mount for the gun; of a longitudinal shaft on the mount, an arm on said shaft adapted by its rotation to operate said firing mechanism and means for automatically deflecting said arm and shaft to normal position after firing.
2. The combination with a breech-loading gun, firing mechanism thereon, a recoil-mount for the gun; of a pivoted arm on the mount for operating said firing mechanism, a lever for actuating said arm; and means operated by continued movement of said lever for re-

leasing said arm from the influence of said lever.

3. The combination with a breech-loading gun, firing mechanism thereon, a recoil-mount for the gun, of a pivoted arm on the mount 60 for operating said firing mechanism, a lever for actuating said arm; and means operated by continued movement of said lever for releasing said arm from the influence of said lever, and means for returning said arm to 65 normal position.

4. The combination with a breech-loading gun, firing mechanism thereon, a recoil-mount for the gun, of a pivoted arm on the mount 70 for operating said firing mechanism, a lever for actuating said arm; and means operated by continued movement of said lever for releasing said arm from the influence of said lever, means for returning said arm to normal position and means for returning the lever 75 to normal position.

5. The combination with a breech-loading gun, firing mechanism thereon, and a recoil-mount for the gun; of a pivoted arm on the mount adapted in its rotation to operatively 80 engage said firing mechanism, a hub for rotating said arm, and an operating-lever hinged to said hub and adapted to swing out of operative position.

6. The combination with a breech-loading 85 gun, firing mechanism thereon, a recoil-mount for the gun; of a pivoted arm on the mount adapted in its rotation to operatively engage said firing mechanism, a hub for rotating said arm, and an operating-lever hinged to said 90 hub and adapted to swing out of operative position and prevent rotation of said arm.

7. The combination with a breech-loading gun, firing mechanism thereon, and a recoil-mount for the gun; of a bearing on a non-recoiling portion of said mount, a shaft rotatively mounted in said bearing, an arm integral with said shaft adapted to actuate said firing mechanism, a firing-handle for actuating and thereafter releasing said shaft, a 100 spring for returning said shaft, and a spring for returning said handle.

In testimony whereof I have signed my name to this specification in presence of two witnesses.

VERNON C. TASKER.
